Primary Examiner — Vy N Koenig*Assistant Examiner* — Michelle M Reeves(74) *Attorney, Agent, or Firm* — Luedeka Neely Group, P.C.(57) **CLAIM**

The design for a connecting sleeve for a height adjustable table, as shown and described.

DESCRIPTION

FIG. 1 is a front view of a connecting sleeve for a height adjustable table showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a top perspective view thereof; and,

FIG. 8 is a bottom perspective view thereof.

The broken lines in the drawings are included for the purpose of illustrating unclaimed features and form no part of the claimed design.

1 Claim, 8 Drawing Sheets(56)
